UNITED STATES PATENT OFFICE

2,470,233

FESTOON BRACKET

James H. Boye, Chicago, Ill., assignor to James H. Boye Manufacturing Company, Chicago, Ill., a corporation of Illinois

Application September 13, 1945, Serial No. 616,022

6 Claims. (Cl. 160—330)

1

The invention relates to drapery supports and has reference in particular to an improved form of adjustable supporting means for a festoon ring.

An object of the invention resides in the provision of an adjustable adapter which may have a wide variety of positions on a supporting bracket and which adapter is designed for releasably engaging and holding a festoon ring.

Another object is to provide an adapter which will yieldingly clamp a festoon ring to securely and firmly hold the same although permitting release of the ring and which will not require the manipulation of any screws or bolts.

A further object is to provide an adapter for securing to a bracket in a variety of positions and which adapter will have indexing means cooperating with the bracket to locate and hold the adapter in adjusted position.

With these and various other objects in view, the invention may consist of certain novel features of construction and operation as will be more fully described and particularly pointed out in the specification, drawings and claims appended hereto.

In the drawings which illustrate an embodiment of the device and wherein like reference characters are used to designate like parts—

Figure 1 is a vertical sectional view illustrating a festoon ring in supporting relation by the adapter and bracket combination of the invention;

Figure 2 is a view in elevation of the reverse side of the bracket and festoon ring from that shown in Figure 1;

Figure 3 is a sectional view illustrating the festoon ring as supported by the bracket and adapter combination in a different position from that shown in Figure 1; and

Figures 4 and 5 are perspective views of the adapter.

Referring more particularly to the drawings, the festoon ring indicated by numeral 10 is for supporting drapery and the like which is passed through the ring, the same having a round cross section for the purpose. For such use it is desirable that the ring be supported in different positions relatively to a supporting wall and accordingly the invention provides an adapter indicated by numeral 12 having a plurality of indexed positions on a bracket 14.

The bracket 14 includes a shank portion 16 longitudinally ribbed at 18 for strengthening purposes and a supporting portion 20 having a right angle bend with respect to the shank. One or more openings 22 may be formed in the portion

2

20 for receiving the screws 24 which secure the bracket to a wall or the like. The shank portion of the bracket therefore projects outwardly of the supporting wall and said projecting end is provided with a center opening for receiving the screw 26 and with indexing openings 28 formed around the center opening at the same radial distance therefrom.

The adapter 12 includes a base 30 having a center opening 31 and having upstanding prongs 32 disposed to the respective sides of the center opening. The prongs are bent upwardly from the metal of the base, having a substantially right angle relation therewith and both prongs in cross-section approximate a U as clearly shown in Figure 4. As a result of the U form given to the prongs it will be observed that a trough extends longitudinally of the prongs and which gives them a shape substantially similar to that

20 of the transverse recesses 34 provided in the festoon ring 10. At one end of the base of the adapter the metal is indented as shown in Figure 4 to form an indexing protuberance 36 on the underside of the base, as best shown in Figure 5.

25 The protuberance seats in one of the openings 28 to hold the adapter in the desired indexed position.

The festoon ring is provided with a section 30 providing the transverse recesses 34 and which is rendered decorative by the provision of bulbous portions 38 with a recess being located between each pair of said portions. The adapter is secured to the bracket by the screw 26 and which is tightened when the adapter has been rotated to the desired adjusted position. This will locate the protuberance 36 in one of the indexing openings 28 and thus the adapter is locked and held to the bracket in said desired position.

The festoon ring is fitted to the adapter by 40 locating the prongs 32 in the transverse recesses 34. The spacing between the prongs is such that a tight fit is provided for the festoon ring. It is desirable that the prongs have a slight spreading when the ring is inserted to thereby maintain tension on the ring and hold the same firmly to the adapter. Also the hollow shape of the prongs 32 produces additional holding action on the ring since each prong in cross-section is similar in outline to the recess receiving the same. The ring 45 has a press fit on the adapter and is resiliently held, being releasable at any time, and which operations do not require the manipulations of any screws or bolts.

50 Figure 2 illustrates the rotative positions of the adapter to vary the angle of the festoon ring.

Figure 3 illustrates another manner of assembling the ring with respect to the adapter and bracket. In both methods of use of the ring the rotative adjustability of the adapter may be employed to vary its position on the bracket. When the screw 26 is tightened the adapter is locked in place on the bracket by the protuberance 36 seating in one of the openings 28. It is only necessary to release the screw and rotate the adapter to vary its position and the inclination of the festoon ring.

The invention is not to be limited to or by details of construction of the particular embodiment thereof illustrated by the drawings as various other forms of the device will of course be apparent to those skilled in the art without departing from the spirit of the invention or the scope of the claims.

What is claimed is:

1. In a device of the character described, in combination, a bracket for securement to a supporting structure, an adapter releasably and rotatably secured to the bracket, said adapter and bracket having coacting means for holding the adapter in adjusted rotative position, spaced supporting prongs provided by the adapter, and a drapery ring releasably engaged by said prongs for supporting said ring from the bracket.
2. In a device of the character described, in combination, a bracket having a shank portion and an angularly disposed supporting portion, an adapter releasably and rotatably secured to the shank portion at the outer end thereof, said adapter and bracket having coacting means for holding the adapter in adjusted rotative position, spaced supporting prongs projecting from the base of the adapter, and a drapery ring releasably engaged by said prongs for supporting said ring from the bracket.
3. In a device of the character described, in combination, a bracket for securement to a supporting structure, an adapter including a base portion and spaced supporting prongs extending from said base, securing means having connection with the base of the adapter centrally thereof for pivotally securing the adapter to the bracket whereby the adapter may rotate about said means as an axis, and means on the adapter having co-

action with the bracket for holding the adapter in adjusted rotative position.

4. In a device of the character described, as defined by claim 3 wherein said spaced supporting prongs are substantially U-shaped in cross section with the concave surface of each prong being directed outwardly and opposite to that of the other prong.

5. A drapery ring support comprising, in combination, a bracket having a shank portion and an angularly disposed supporting portion, an adapter rotatably secured to the shank portion at the outer end thereof, said adapter including a base portion providing spaced projecting supporting prongs, means on the base of the adapter having coaction with the bracket for holding the adapter in adjusted rotative position, and a drapery ring having transverse recesses for receiving the supporting prongs whereby said ring is releasably fixed to said adapter.

6. A drapery ring support comprising, in combination, a bracket for securement to a supporting structure, said bracket having a plurality of openings formed therein adjacent the free end thereof, an adapter including a base portion providing spaced projecting supporting prongs, a securing screw releasably securing the adapter to the bracket adjacent the free end thereof whereby the adapter may be rotated about said screw as an axis when the same is released, means on the base of the adapter having coacting relation with said openings in the bracket for holding the adapter in adjusted rotative position, and a drapery ring having transverse recesses for receiving the supporting prongs whereby said ring is releasably fixed to said adapter.
